US0D1084335S

(12) **United States Design Patent** (10) **Patent No.:** **US D1,084,335 S**
(45) **Date of Patent:** **** Jul. 15, 2025**

(54) **SURGICAL BLADE CARTRIDGE**

(71) Applicant: **Stryker European Operations Limited**, Carrigtwohill (IE)

(72) Inventors: **Seamus Gilhooley**, Athenry (IE); **Greg McEwan**, Mattawan, MI (US); **Paul Shiels**, Albuquerque, NM (US)

(73) Assignee: **Stryker European Operations Limited**, Carrigtwohill (IE)

(**) Term: **15 Years**

(21) Appl. No.: **29/864,810**

(22) Filed: **Jun. 22, 2022**

(51) LOC (15) Cl. **24-02**

(52) U.S. Cl.

USPC **D24/147**

(58) **Field of Classification Search**

(57) **CLAIM**

The ornamental design for a surgical blade cartridge as shown and described.

DESCRIPTION

FIG. 1 is a top, front, right side, perspective view of a surgical blade cartridge;

FIG. 2 is a bottom, rear, left side, perspective view thereof;

FIG. 3 is a top view thereof;

FIG. 4 is a bottom view thereof;

FIG. 5 is a left-side view thereof;

FIG. 6 is a right-side view thereof;

FIG. 7 is an enlarged front view thereof; and,

FIG. 8 is an enlarged rear view thereof.

The broken lines depict portions of the surgical blade cartridge that form no part of the claimed design.

1 Claim, 4 Drawing Sheets
